UNITED STATES PATENT OFFICE.

S. C. TALCOTT, OF ASHTABULA, OHIO.

IMPROVEMENT IN CARRIAGE-HUB BANDS.

Specification forming part of Letters Patent No. 43,238, dated June 21, 1864.

To all whom it may concern:

Be it known that I, S. C. TALCOTT, of Ashtabula, in the county of Ashtabula and State of Ohio, have invented certain new and useful Improvements in Carriage-Hub Bands; and I do hereby declare that the following is a full and complete description of the construction and operation of the same, reference being had to the accompanying drawings, making a part of this specification, in which—

Figure 1 is a perspective view. Fig. 2 represents the band and cap separate. Fig. 3 is a sectional view.

Like letters of reference refer to like parts in the different views.

My improvement relates to a carriage-hub band.

In the several figures, A represents the band, which is of the usual form; B, the cap, attached to the band in the manner described, as follows: On the inside of the band, near the outer edge, where the cap comes, is formed the rim or flange C, which is curved inward at C, making a depression, as represented in Figs. 2 and 3.

Fig. 2 is a view of the band and cap detached, representing the inside of the cap and the devices for securing it to the band, which consist of the curved spring D, or its equivalent, secured at one end in the clutch E, and the other end is attached to the sliding catch F; as represented. This catch extends till about the center of the cap, where it is connected to the button H, on the outside, by a pin or rivet, d, (shown in Fig. 3,) there being a slot, h, through the thickness of the cap for the pin to move in. The sliding catch F passes through the guide f, secured to the cap near the edge, and this catch is in a line with

the clutch E, near the opposite edge of the cap, as represented in Figs. 2 and 3.

The cap is placed on the band in such a position that the sliding catch F will come in the center of the depression C, and the clutch E will fit into a place beveled out in the inside of the flange C. (Shown in Fig. 3 and indicated at b in Fig. 2.)

The cap is fastened in its place on the band by putting the clutch E inside of the rim in the depression b and moving down the sliding catch F by the button H, as indicated by the red lines in Fig. 3, until the cap fits in around the rim e of the band. Then by removing the pressure from the button H, the catch F is sprung into the hole a in the band, as seen in Fig. 3, by the spring D, or the catch will spring into place by pressing on the cap, thus most conveniently and nicely attaching the cap to the band, and in such a way as to be most secure and immoveable in its position, and it is so readily detached from the band at any time when desired by simply moving down the button H, which disengages the catch F, and the cap comes off, and the devices are in no way liable to get out of repair.

This arrangement is much less expensive than any in ordinary use, and much neater, more readily taken off and put on, and is not liable to be run off when the carriage is in use.

What I claim as my improvement, and desire to secure by Letters Patent, is—

The clutch E, spring D, cap B, button H, in combination, the flange C and band A, substantially as and for the purpose set forth.

S. C. TALCOTT.
